CONTAINER AND METHOD OF MAKING
THE SAME

Henry E. Braloff, Rockville Centre, N. Y.

Application May 14, 1942, Serial No. 442,972

3 Claims. (Cl. 229—5.5)

This invention relates generally to containers and is more particularly directed to a container composed of fibrous material and the method of making the same.

While containers composed of fiber, as cardboard and the like, are available for the packaging of goods of various kinds, they have not been found to be entirely satisfactory in the packing and distribution of many materials, where their use would be economically advantageous. For example, in the distribution of oils, paints and other liquid and semi-liquid, and semi-plastic materials, as well as many dry products, which are subject to rapid deterioration unless protected by moisture-proof packages, the use of fiber containers has been more or less limited, largely because of the fact that it has been impossible heretofore to economically produce a container that will not only be durably leak-proof and impervious to moisture penetration, but will possess the requisite ruggedness without unduly increasing the gross weight of the packaged product. Obviously, in the marketing of paints, oils, semi-liquids and similar materials, which are customarily dispensed in so-called drums of five gallon or greater capacity, the gross weight is an important desideratum, as is also the capacity of the container to withstand rough handling in shipping.

Therefore, it is the principal object of this invention to provide an all fiber container of a simple rugged construction, which is relatively light in weight and is particularly responsive to the requirements for packaging liquids and semi-liquid material, in that it is leakproof and impervious to moisture penetration in a degree which renders it possible to store the packaged goods for long periods of time, without the constituent material of the container being detrimentally affected, with the resultant leakage and deterioration of the product that is common in the use of existing types of fiber containers.

It is also an important object of this invention to provide a container possessing the aforesaid advantages and characteristics, which may be conveniently hermetically sealed by the packer of the contained product with a closure which may be subsequently readily removed for dispensing the product and replaced, as desired, to restore the seal and protect the remaining contents of the container against deterioration.

Another object of this invention is to provide an all fiber container, as aforesaid, in which the ends thereof are assembled in the container in 55

a manner to appreciably reinforce the entire structure and at the same time effect a jointure of the end-forming elements with the continuous wall of the container that is proof against fluid leakage and effectively prevents moisture penetration from within or without.

A further object of my invention is to provide an all fiber container in which a material impervious to moisture is incorporated in the fiber wall and the end-forming elements, to become virtually a part thereof, the end-forming elements being reinforced against bending forces and interlocked with the wall of the container in a fluid-proof jointure, to resist separation under constant and shifting loads.

My invention also contemplates a container having the foregoing characteristics and a method of producing the same in a manner which may be readily practiced, so that a container conforming to my invention may be most economically manufactured and thereby provide for more extensive use of fiber containers in those industries in which the use of existing fiber containers has been found to be commercially impracticable in packaging their products for distribution.

Other objects and advantages flowing from the practicing of my invention will become manifest as the description proceeds and I would have it understood that I reserve unto myself all rights to the full range of equivalents, in structure and avenues of use, to which I may be entitled under my invention in its broadest aspect, as defined by the appended claims.

35 In the accompanying drawings, I have shown a preferred form of container conforming to my invention, as produced in accordance with my simplified and economical method of manufacture.

40 In the drawings:

Figure 1 is a view in elevation, partly in section of a container embodying my invention.

45 Figure 2 is a magnified view in elevation of a section of the upper left hand corner of the container shown in Figure 1.

Figure 3 is a sectional elevation of a part of a container, showing a modified form of closure and retaining means.

50 Figure 4 is a sectional elevation of the closure shown in the structure of Figure 3.

Figures 5 and 6 are respectively fragmentary sectional views, illustrative of modifications of the sealing or retaining ring shown in Figure 3.

Figure 7 is a fragmentary sectional view show-

ing a retaining ring of the form shown in Figure 3, as it may function in lieu of the retaining ring of Figures 1 and 2, and

Figures 8 and 9 are respectively views in elevation of fragments of the retaining ring of Figure 7, showing alternative interlocking means on the outer circumference thereof.

Referring now to the drawings in detail, in which like characters of reference are employed to designate similar parts in the several views, the container as herein shown is of a cylindrical configuration and is one such as may be utilized for liquids and semi-liquid material, embodying an outer tubular wall 7 and an inner wall formed by a tubular sleeve 8 inserted within the outer wall-forming tube 7, to provide a container body wall of the requisite circumference, thickness and internal diameter.

These body-forming tubes are preferably composed of spirally wound pressed chipboard, the convolutions or windings forming each of the constituent laminations mating in butt joints and being bonded to the convolutions upon which they are superimposed by an adhesive agent, as silicate of soda, to produce a section of the requisite thickness. In producing the inner tubular sleeve 8, a layer of metal foil 9 is introduced at a predetermined stage of the chipboard winding operation and spirally superimposed thereon, with the edges of its convolutions in overlapping engagement, the subsequent windings of chipboard or fiber being in turn superimposed upon the metal foil, to attain the desired wall thickness, as described. A permanent bond between the metal foil surfaces and the opposed fiber surfaces and the union of the overlapped surfaces of the metal foil is obtained by coating the foil with a cementitious material, as a casein adhesive, the metal foils as thus embedded in the fibre tube and the bonding of the chipboard lamina, producing a tube having all of the attributes of a homogeneous structure, similarly to the outer tube, in resisting disintegration, together with the strength and rigidity that flow from the spirally wound construction. Preferably the metal foil is introduced in the winding of the sleeve 8, when the wall section has been built up to approximately one-half of its ultimate thickness, it being manifest that the metal foil with its overlapping convolutions presents a continuous surface internally of the inner and outer faces of the tube or sleeve 8, coextensive with the linear dimensions of the tube, which is impervious to fluid penetration, as would obtain in an all metal wall, the overlying and concealing chipboard windings effectively protecting the thin metal foil against damage that is common in those containers in which the moisture-proof coating or material is applied to the inside thereof.

In the production of the container body, tubing of the required diameter may be formed in any convenient lengths, as described, and then subdivided in the lengths appropriate to form the aforesaid outer wall section 7 and the inner sleeve 8, the latter being shorter than the former so that when it is entered in the section 7, its top and bottom ends will be approximately equidistantly spaced from the contiguous ends of the outer wall section 7, as indicated at 10 and 11, in Figure 1. The external diameter of the inner sleeve 8 corresponds approximately to the internal diameter of the outer tube 7, the tolerance being just sufficient for entering the sleeve within the tube 7 and forcing it to its ultimate co-operating position therein under axially applied

pressure, in a so-called force-fitting operation, the two tubular sections being frictionally united throughout the area of their opposed surfaces, so that the effect of a unitary structure in strength and rigidity is attained.

In the container of Figures 1, 2 and 7, a base 12 of a diameter corresponding to the internal diameter of the tubular wall section 7 is then inserted therein with its upper marginal surface 10 pressed into close association with the lower end of the inner sleeve 8. This base is preferably formed of laminations of pressed chipboard between which a layer of metal foil 13 is interposed and united to the fiber on either side thereof, by an adhesive, as previously described, the chipboard laminations treated with a bonding agent, as the previously recited silicate of soda, being inseparably united in a pressing operation, whereby the metal foil becomes, in effect, an integral part of the base unit, a series of concentric grooves 14, 15 and 16, being pressed into the base surface to effect an opposite displacement of the base material in the formation of the reinforcing ribs 17, 18 and 19 to resist bending forces.

A retaining ring 20 of spirally wound chipboard, produced similarly to the tube 7, having an external diameter approximately corresponding to the internal diameter of the outer wall tube 7 is next entered therein under pressure in a force-fit operation. The upper edge of this ring adjacent its outer face is undercut, as at 20a, to impart to it a stepped formation, the undercut portion abutting upon the juxtaposed surface of the base in alignment with the opposed end of the inner sleeve 8, while the longer portion 20b is entered in the outermost base groove 14. Therefore, as the ring is urged into its ultimate position within the sleeve 8, the base is pressed into close frictional association with the end of the sleeve in an end displacement or deformation of the sleeve material in conforming to the portion of the marginal rib 17 and the relatively depressed surface in the peripheral zone of the base upon which it abuts, to interlock the opposed surfaces in a plurality of zones or horizontal planes and provide an hermetic jointure, the seal being augmented by the laterally exerted pressure induced by the interengagement of the ring flange 20b and the base groove 14, supplementing the frictional engagement of the periphery of the base with the opposing wall of the tube 8.

If desired, the ring 20 may be composed of two force-fitted telescoped sections of the appropriate lengths to obtain the required stepped upper edge formation, for engagement with the base member as just described.

Following the assembly of the base-forming elements in the container structure, as just described, the outer surface of the wall-forming tube 7 is peripherally grooved, as at 21, while the inner surface of the retaining ring 20 is grooved as at 22 and 23, the groove 21 being staggered relatively to the two ring grooves, for circumferential reinforcement of the mated surfaces.

The closure 24 is formed similarly to the base 12 and includes a layer of metal foil 24a embedded therein, the jointure of the closure with the container being effected by a split ring 25, otherwise corresponding to the base retaining ring 20, which similarly functions to maintain the closure in frictional engagement with the upper end 10 of the inner sleeve 8, to cooperate therewith in the formation of an hermetic jointure of the opposed abutting surfaces. As in the

base assembly, the sealing at this point is supplemented by the force-fit engagement of the periphery of the closure with the wall 7 of the container and the augmented security afforded thereto by the lateral pressure of the protruding edge 25a of the ring 25 entered in the closure groove 26. Similarly to the base-retaining ring, the closure-retaining ring 25 is circumferentially grooved as at 27 and 28, while the periphery of the wall-forming section 7 is grooved as at 29, for likewise stiffening or reinforcing these projecting surfaces against bending under vertically applied forces. The opposed ends of the split closure-retaining ring embody a tongue 30 and a complementary slot 30a formed for interlocking engagement, the slot and tongue respectively being of the thickness of the wall, so that when the tongue is entered in the slot the cross-sectional area of the ring is uniform throughout its circumference, the ring being seated within the container wall 7 in closure-retaining position, as described, with the tongue and slot in interlocking engagement and the opposed tongue and slot defining surfaces mated to provide, in effect, an uninterrupted locking ring. To remove the closure, the tongue may be pried out of engagement with the embracing slot by means of any suitable implement, and the ring then dislocated inwardly in a slight upward movement for contracting disengagement from the closure and the surrounding wall of the container. To restore the seal, following the reapplication of the closure, the tongue and slot are interlocked and the ring pressed into seated position in engagement with the closure and the wall of the container, as previously described.

As in the base assembly, the ring 25 may consist of two force-fitted telescoped tubular sections of appropriate lengths, to obtain the requisite stepped edge formation for engagement with the closure in the manner previously set forth. Both of the constituent sections may be split and embody a tongue and slot interlock corresponding to the counterparts of the ring 25, to admit of their disconnection from the container, as a unit, or only the inner section may include this interlock, the outer ring section being continuous or of a split type, preferably with an oblique line of cleavage.

In the embodiment of the invention shown in Figure 3, the closure 40 is preferably composed of two concentric discs 42 and 43 of different diameters, of pressed fiber, which are cemented together to form a diaphragm type unit having a stepped edge, as at 41, and having embedded therein a layer of material impervious to moisture, as indicated at 40a, similarly to the closure of Figures 1, 2 and 7. In addition to this embedded layer of moisture resistant or repellent material, or in lieu thereof, the inner surface of the closure may be faced with such a material. The closure 40, similarly to the closure 24, is pressed into seated position within the body section 7 of the container, in abutting engagement with the contiguous end of the inner sleeve 8. A retaining ring 44, preferably of hard vulcanized fiber, is then forced into the end of the body section 7 to an ultimate position in engagement with the horizontal and vertical defining surfaces of the circumferential stepped edge 41, the cross-sectional dimension of the wall of the ring corresponding to the width of the base of the stepped edge, so as to insure a tight fit and form an hermetic jointure between the closure and the container body. The ring 44 normally may be

slightly elliptical in shape, so that as its major diameter portion is forced into the container body, the ring will expand in conforming engagement with the opposed surface of the body section 7, to increase the effective pressure between the ring and the container wall.

Following the seating of the ring 44, as just described, the opposed circumferential surfaces of the ring and of the body section 7 are interlocked in the formation of the complementary circumferential grooves and beads, as at 45 and 46, in an appropriate crimping operation.

While the ring 44 may be continuous, to facilitate the removal of the closure and afford access to the contents of the container, a split ring is preferable, the separable ends thereof being normally interlocked by the interengagement of the tongue 47 and the complementary slot 48, the tongue being provided with a tab 49, whereby its dislocation from the slot may be readily accomplished in an inward contracting movement of the ring.

In the modified forms of the retaining ring 44, as shown in Figures 5 and 6, the efficacy of the seal is enhanced. The ring of Figure 5, as will be seen, embodies a circumferential flange 50 at one end which is adapted to overlie the vertical seam formed by the mating of the opposed surfaces of the ring and body section 7,

30 in abutting engagement with the outer end of said section, while, as shown in Figure 6, the flange 50 instead of terminating in a horizontal plane in registration with the outer wall of the container, is extended downwardly thereover, as 35 at 51. This extension 51, disposed parallel to the body of the ring 44 forms an annular slot, in which the end of the body section 7 is entered in close frictional association with the defining surfaces thereof, in the seating of the ring in engagement with the closure 40, as previously described.

The containers of Figures 3, 5 and 6 may embody a base assembly conforming to the closure assemblies shown in such figures, with the exception that a continuous retaining ring would be used in substitution for the removable split ring 44 of the closure assembly, or, if preferred, the base assembly may correspond to that shown in Figures 1 and 2. Where the closure 40 of the diaphragm type is employed, whether in the formation of one or both end seals, it will be apparent that in addition to the frictional jointure of the closure with the container and retaining ring surfaces, the pressure diaphragm characteristics which flow from the superimposed smaller disc section which forms the outer face of the closure add materially to the maintenance of an effective seal.

The closure assembly shown in Figure 7 corresponds generally to that of the showing of Figures 1 and 2, the closure-retaining means consisting of two rings 52 and 53 of unequal lengths and different diameters. The ring 52 is adapted to be telescopically entered in the ring 53 seated in engagement with the surrounding container body section 7 and the marginal surface of the closure 24, in alignment with the end surface of the inner sleeve 8 of the container, for projection of its lower edge into the outermost groove 26 of the closure, in the manner and for the purposes previously set forth. The two rings 52 and 53 may be subsequently interlocked with the body section 7 by the simultaneous formation of the complementary interengaged ribs and recesses, indicated at 54 and 55 in a crimping op-

eration, the outer ring 53 being circumferentially grooved, as at 56, for the reception of the circumferential bead 57 of the inner ring 52, as shown in Figure 8, or, in lieu of this continuous bead, the inner ring 52 may be provided with a plurality of relatively spaced peripheral protuberances, as at 58, as shown in Figure 9, to enter the groove 56 of the outer ring.

The outer ends of the two rings 52 and 53 may terminate in registration, as shown, or the inner ring may be flanged as in the rings of Figures 5 and 6, to overlie the registering ends of the outer ring and the surrounding body section 1 of the container.

As will be apparent, in all of the embodiments shown, the end-forming members are engaged with the inner sleeve 8 of the container under pressure and locked in sealing position in a manner to produce a jointure of tortuous characteristics, which produces a most effective hermetic seal for the container, which may be further rendered fluid-penetration proof by the application of a suitable adhesive to the meeting surfaces of the cooperating components of the end-forming assemblies.

If desired, the opposed surfaces of the outer and inner tubular wall-forming elements 1 and 8 may be bonded with a suitable adhesive and, likewise, the cooperating surfaces of the end assemblies may be cemented to the portions thereof with which they engage, but this is unnecessary in conforming to my method and, of course, would, obviously, add to production costs. Also, in addition to incorporating a substantially centrally lap-wound layer of metal foil in the inner sleeve, the inner surface of said sleeve may be rendered impervious to moisture and the detrimental action of substances that may be packed in the container by suitable coatings or facing with the appropriate resistant material, or such coatings or facing may be employed in lieu of the layer of moisture-proof metal foil embedded in the sleeve.

For packaging certain different materials, the container may be variously treated, internally and externally, to protect the fiber or the contents against possible deterioration, as the case may be. For example, in a container designed for packaging oils, grease and similar viscous materials, an asphalt coated chipboard is preferably used to form the inner wall of the container, the outer wall being of the same material or of untreated chipboard as herein shown. For food-stuffs, the container is preferably lined with Cellophane, while the outer wall may be a lamination of the same material, or asphalt or chipboard, as may be deemed necessary or desirable.

From the foregoing, it will be manifest that I have provided a container that may be rapidly and economically produced and will possess those attributes that are essential in the provision of a practical fiber container for commercial and industrial purposes, one that is especially responsive to the requirements of marketers of liquids and semi-liquid materials, for the reasons hereinbefore set forth.

I claim:

1. A container comprising a fiber body formed of inner and outer tubular sections, the inner section embodying a coextensive surface of material impervious to moisture embedded therein, the ends of said inner section being equidistantly spaced from the contiguous ends of said outer

section, a pair of end-forming members, each being entered in said outer section in peripheral engagement therewith and in surface abutting engagement with the juxtaposed end of said inner section to effect an hermetic jointure of the opposed surfaces, each of said end-forming members being provided with a groove adjacent the periphery thereof and a retaining ring for reinforcing the security of said jointure, entered in each end of said outer section in circumferential engagement therewith, one end edge of said ring having a stepped formation in abutting engagement respectively with the groove and the peripheral edge of said end-forming member, the other edge of said ring being in registration with the container base-defining edge of said outer section.

2. A container comprising a fiber body formed of inner and outer tubular sections, the inner section embodying a coextensive surface of material impervious to moisture embedded therein, the ends of said inner section being spaced inwardly of the contiguous ends of said outer section, a pair of annular end-forming members, each being entered in said outer section in peripheral engagement therewith and embodying coacting reinforcing grooves and ribs formed on the opposite surfaces thereof, and a retaining ring entered in each end of said outer section in circumferential engagement therewith, the entered end of said ring being conformed to enter one of the grooves of said end-forming member in proximity to the periphery of said member and to bear upon said end-forming member beyond said groove, in alignment with the end of said inner section in abutting engagement with the opposite surface of said end-forming member in the area of the marginal one of said reinforcing ribs and outwardly thereof to the periphery of said end-forming member, the opposed meeting surfaces of said sections and said end-forming member forming an hermetic seal for the end of said container.

3. A container comprising a body formed of inner and outer tubular sections, the ends of said inner section being spaced inwardly of the contiguous ends of the outer section, a pair of flat annular end-forming members, each being entered in said outer section in peripheral engagement therewith and embodying coacting concentric reinforcing grooves and ribs formed on the opposite surfaces thereof, and a retaining ring entered in each end of said outer section in circumferential engagement therewith, the entered end of said ring engaging the outer surface of said member and exerting pressure thereon to urge said member into frictional engagement with the opposed end of said inner section, a portion of said ring being engaged within the outermost groove of the end-forming member to exert pressure laterally thereof, said inner and outer tubular sections and said retaining rings being formed of spirally wound pressed fiber with their mated defining edges in butting engagement to present uniform internal and external surfaces, the inner tubular body section having a spirally wound layer of a material impervious to moisture embedded in the fiber windings, the convolutions of said material being disposed in overlapping engagement along their edges to form a continuous surface coextensive with the area of said inner section.

HENRY E. BRALOFF.
